UNITED STATES PATENT OFFICE.

GUY B. COLLIER, OF KINDERHOOK, NEW YORK.

INTERNAL-COMBUSTION MOTOR.

1,040,277.

Specification of Letters Patent.

Patented Oct. 8, 1912.

Application filed January 3, 1912. Serial No. 669,241.

To all whom it may concern:

Be it known that I, GUY B. COLLIER, a citizen of the United States, residing at Kinderhook, in the county of Columbia and State of New York, have invented certain new and useful Improvements in Internal-Combustion Motors; and I do hereby declare the following to be a full, clear, and exact description of the invention, such as will enable others skilled in the art to which it appertains to make and use the same.

The present invention relates to internal combustion motors, and more particularly to the valve mechanisms for this type of motor which comprise a valve having a movement of rotation or oscillation in its seat. It is conducive to the efficient operation of this type of valve that it be operated with a small expenditure of power and that a gas tight joint be maintained under varying conditions of temperature and with long continued usage. This result can be best secured if the pressure upon the valve is evenly balanced and only sufficient excess pressure is exerted upon the valve to maintain it in proper engagement with the seat. When the valve is placed in a condition of substantial static equilibrium in this manner the wear upon the valve and seat is reduced to a minimum and the mechanism may be operated for an indefinite period without replacement.

The object of the present invention is to provide a valve mechanism of this type which affords large port and passage areas for the admission and exhaust of the gases from the cylinder without leakage of the same and which may be operated with a small expenditure of power while maintaining a gas tight joint indefinitely.

With this object in view, one feature of the invention consists in the provision of means for balancing the valve in synchronism with the changes of pressure in the cylinder so that the valve is maintained permanently in a condition of substantial static equilibrium.

Still further features of the invention consist in certain novel features of construction, combinations and arrangements of parts hereinafter described and claimed, the advantages of which will be obvious to those skilled in the art from the following description.

55 In the accompanying drawings illustrating the preferred form of the invention;

Figure 1 represents a front elevation of an internal combustion motor embodying the several features of the invention in their preferred forms; Fig. 2 is a section upon the line 2—2 of Fig. 1 looking in the direction of the arrow; Fig. 3 is a sectional elevation taken upon the line 3—3 of Fig. 2 looking in the direction of the arrow; Fig. 4 is a sectional elevation illustrating a modified construction for balancing the vertical component of the pressure upon the valve; and Fig. 5 is a sectional elevation illustrating another modified construction for balancing the vertical component of the pressure upon the valve.

In the illustrated embodiment of the invention, the motor is indicated at 1 and consists of the usual water jacketed cylinders indicated at 2, and each provided with pistons 3 operatively connected to the crank shaft 4 through connecting rods 5. A single valve supplies two adjacent cylinders and the valve chamber is provided with a water jacketed valve seat housing 6 having a port 7 opening into each of the cylinders.

The rotary valve is indicated at 8 and is provided with an inlet port 9 and an outlet port 10 which open into separate chambers formed in the interior of the valve and divided by a partition 11. The valve is rotated continuously to bring the inlet and outlet parts of the valve successively into register with the cylinder ports by a vertical shaft 13 which is driven from a valve shaft 15 through intermeshing bevel gears 16 and 17. As will be noted from an inspection of Fig. 1, the cranks of the two adjacent cylinders are positioned 180° apart and the valve shaft 15 is driven at one half the speed of the crank shaft so that the inlet and exhaust ports of the valve are brought into register with each cylinder port at the proper time.

The above described construction forms no part of the present invention, and is fully described in the co-pending application of Wales, Serial No. 658,526, filed October 24, 1911.

This valve is employed in connection with a gas engine of the four-cycle type, in which the successive strokes of the piston are explosion, exhaust, suction and compression. During the exhaust and suction strokes of the piston, the exhaust and inlet ports respectively register with the cylinder port, but during the explosion and compression

strokes of the piston, the cylinder port is closed by the blank wall of the valve and the pressure of the gas in the cylinder upon this wall causes an unbalanced pressure to be exerted upon the valve if not compensated for in some manner. In the present invention the valve is balanced laterally by applying to the valve diametrically opposite each cylinder port a pressure which is equal and oppositely directed to the pressure applied to the valve through the cylinder port. The valve is made frusto-conical in form, as with this type of valve a gas tight joint may be maintained with repeated contraction and expansion and with long continued wear. The vertical component of the unbalanced pressure acting against the inclined wall of the valve, however, tends to force the valve away from its seat, making it desirable to provide some means for balancing the valve axially. In order to neutralize the vertical component of this unbalanced pressure, means are provided for applying an equal and oppositely directed pressure axially of the valve which effectively neutralizes the vertical component of the unbalanced pressure without causing any substantial axial pressure in either direction, thus allowing the valve to be firmly seated without an unbalance pressure. In the simplest and most efficient form of the invention which has yet been devised, connections are provided which allow a free transmission of pressure from the cylinders to a series of chambers so arranged that the pressure in either or both of the cylinders tending to unbalance the valve will always be maintained in the chambers and applied to the valve in a manner to balance it.

The valve 8 is frusto-conical in form, as shown clearly in Fig. 3 and rotates in a valve seat 20 which is secured in the valve seat housing 6. Each of the cylinders is provided with a pressure pipe 22 connecting the upper portion of the cylinder with two pressure chambers 24 and 25 formed in the top and bottom of the valve seat 20 diametrically opposite to the port 7 of the cylinder. The total lateral pressure exerted upon both the top and bottom of the valve by each pair of chambers is equal to the pressure exerted through the opposite cylinder port, thus balancing the valve laterally without cramping in its seat. The two sets of chambers are separated from and entirely independent of one another so that no opportunity is afforded for leakage from one chamber to the other.

In order to balance the vertical component of the normal pressure exerted upon the wall of the valve, a piston 30 is rigidly connected to the upper portion of the valve by a rod 32 secured to the valve at 33. The piston 30 is slidably mounted in an auxiliary cylinder 34 and is provided with a packing ring 35 to prevent a leakage of gas and oil past the piston. The cylinder 34 is secured to the top of the valve casing and is provided in its head with chambers 36, each of which is connected to one of the cylinders by a branch pipe 37 leading from the main pipe 22. The chambers 36 are each provided with a dummy piston 40 having provision for a slight movement in the chambers and bearing upon the upper face of the piston 30 in order to effectually seal each chamber and prevent a leakage of the gas from one chamber to the other. In order to press the dummy pistons firmly against the face of the piston 30, a recess is formed in each chamber and an annular flange upon the piston extends into the recess, the upper side of the flange forming an extended surface over which the pressure is applied to maintain the dummy piston in engagement with the piston 30 and assist in balancing the axial thrust. The dummy pistons and main piston are so designed that the combined pressure areas of the dummy piston and main piston in each chamber balance the thrust from one cylinder. With this construction the gas cannot leak past the lower face of the dummy piston as the pressure of the gas is exerted entirely upon the top face of the piston pressing the lower face firmly into engagement with the piston 30 and preventing the entrance of any gas beneath the lower face of the dummy piston to exert an upward pressure on the same. Each of the pistons is provided with a series of piston rings indicated at 42 to prevent any leakage of gas between the piston and the walls of the casing. The valve is provided with a depending rod 41 which is clutched to the shaft 13 in any suitable manner, and in order to prevent the accidental unseating of the valve, a spring 43 is supported upon a sleeve 42 secured to the upper end of the shaft 13 and bears against the upper side of a pin 44 projecting from the rod 41.

In order to eliminate the friction between the valve and its seat, it is necessary to provide means for maintaining a film of oil between the two surfaces and to this end a pair of oil feed pipes 45 are connected with recesses 46 formed in the valve seat. The oil flows from the feed pipes down the recesses and is drawn out of the recesses between the surfaces throughout the entire length of the valve. In order to remove the surplus oil, the recesses 46 communicate at their lower ends with an annular recess 47 formed in the bottom of the valve seat and connected with a return pipe 48, as indicated clearly in Fig. 3. The piston 30 and the dummy pistons 40 are lubricated from an oil feed pipe 50 which leads into the upper portion of the auxiliary cylinder above the piston 30. The oil drops onto the face of the piston 30.

of the piston 20 and is thrown by centrifugal force into an annular recess 51 formed in the casing, from whence it passes out through a return pipe 52.

5 The construction shown in Fig. 4 illustrates a modified form of mechanism for balancing the vertical component of the normal pressure upon the valve. In this construction a hollow cylinder 60 is secured 10 to the top of the valve casing and the upper end of the cylinder is closed by a cap 61. Two bearing members 62 and 63 are threadedly mounted in the interior of the cylinder 60 in spaced relation to one another, 15 and the chambers formed between the bearing member 62 and the top of the casing and the bearing members 62 and 63 respectively are connected with each of the cylinders through the ports 66 and 67. The bearing member 62 is provided with a piston 70 having a plurality of laterally projecting packing rings 71 engaging with co-operating recesses formed in a packing member 72 forming a labyrinth packing 20 and preventing leakage of the gas between the bearing member and piston. The bearing member 62 is provided with a similar piston 75 having packing rings 76 which engage with co-operating recesses formed in 25 a packing member 77. The piston 75 is of a greater diameter than the piston 70 and both pistons are rigidly secured to a vertical rod 78 connected to the rotary valve. The gas in the upper chamber exerts a 30 downward pressure upon the piston 70 and the gas in the lower chamber exerts a downward pressure upon the piston 75 and an opposite upward pressure upon the piston 70, but as the piston 75 has a greater area over 35 which the pressure is effective than the piston 70 the resultant pressure upon both cylinders is in a downward direction and is sufficient to balance the vertical component of the normal pressure upon the valve. It 40 will be noted that both pistons have provision for a slight vertical movement with relation to the bearing members in order to allow for expansion and contraction of the valve under varying conditions of temperature and for wear upon the valve and seat. Each of the pistons is lubricated from an oil feed pipe 80 through which oil is forced 45 under pressure into a duct formed in the bearing member and from thence down into an annular recess 81 and out through a return pipe 82.

Still another construction for balancing the vertical component of the normal pressure upon the valve is illustrated in Fig. 5 50 and consists of two pistons 90 and 91 mounted in tandem and slidably supported in a casing 92 secured to the top of the valve casing. Both of the pistons are rigidly secured to a vertical rod 93 which is connected 55 to the upper portion of the valve and the

pressure is transmitted from the cylinders into chambers 94 and 95 formed above the pistons 90 and 91 respectively. The piston 91 is of a greater diameter than the piston 90, thus causing a resultant downward pressure to be exerted upon the valve by the two pistons as explained clearly with regard to the construction shown in Fig. 4. In order to prevent any leakage of gas out of the chambers, a dummy piston 99 is mounted in 70 each chamber and is pressed upon its co-operating piston to effectually seal each chamber. Each of these pistons 99 is provided with an annular flange 100 at its upper end extending into a co-operating recess formed in the casing in order to afford the proper pressure area and enable it to be tightly seated upon the piston. The contacting surfaces of the dummy piston 99 and the pistons 90 and 91 are lubricated by 80 oil feed pipes 101 and 102 respectively through which the oil is forced. The oil flows down between the pistons and cylinder walls and is thrown by centrifugal force 85 into annular recesses 103 and 104 from 90 whence it is led away by return pipes 105 and 106.

While it is preferred to employ the specific construction and arrangement of parts shown and described, it will be understood 95 that this construction and arrangement is not essential except so far as specified in the claims and may be changed or modified without departing from the broader features of the invention.

Having thus described the invention, what is claimed is:—

1. An internal combustion motor having, in combination, a cylinder, a piston operating therein, a valve chamber provided with a port opening into the cylinder, a valve supported in the chamber and having a valve port arranged to register with the cylinder port, means for continuously rotating the valve, and means for balancing the valve both laterally and axially in synchronism with the changes of pressure in the cylinder, substantially as described.

2. An internal combustion motor having, in combination, a cylinder, a piston operating therein, a valve chamber provided with a port opening into the cylinder, a continuously rotated valve supported in the chamber and having supply and exhaust ports arranged to register with the cylinder port and means for applying to the valve diametrically opposite the cylinder port a pressure which is equal and oppositely directed to the pressure applied to the valve through the cylinder port, substantially as described.

3. An internal combustion motor having, in combination, a cylinder, a piston operating therein, a valve chamber provided with a port opening into the cylinder, a valve supported in the chamber and having supply 130

- and exhaust ports arranged to register with the cylinder port, means for continuously rotating the valve and a plurality of pressure chambers connected with the cylinder and arranged to allow a free transmission of pressure from the cylinder to the chambers to secure a lateral balance of the valve, substantially as described.
4. An internal combustion motor having, in combination, a plurality of cylinders, a piston operating in each cylinder, a valve chamber provided with a port opening into each cylinder, a valve supported in the chamber and having a port arranged to successively register with the cylinder ports and means for applying to the valve diametrically opposite to each cylinder a pressure which is equal and oppositely directed to the pressure applied to the valve through each cylinder port, substantially as described.
5. An internal combustion motor having, in combination, a cylinder, a piston operating therein, a valve seat having a port opening into the cylinder and provided with a pair of pressure chambers formed in the upper and lower portion of the seat diametrically opposite to the cylinder port, connections between the chambers and the cylinder allowing a free transmission of pressure from the cylinder to the chambers, and a continuously rotated valve supported in the seat, substantially as described.
6. An internal combustion motor having, in combination, a plurality of cylinders, a piston operating in each cylinder, a valve chamber provided with a port opening into each cylinder and a pressure chamber located diametrically opposite to each cylinder port, connections between each chamber and its respective cylinder and a continuously rotated valve provided with inlet and exhaust ports and arranged to permanently seal the pressure chambers, substantially as described.
7. An internal combustion motor comprising a cylinder, a valve chamber having a port communicating with the cylinder, a conical rotary valve supported in the chamber, means for balancing the valve laterally and a piston connected to the valve and arranged to balance the valve axially, substantially as described.
8. An internal combustion motor having, in combination, a cylinder, a piston operating therein, a valve chamber provided with a port opening into the cylinder, a valve supported in the chamber and having supply and exhaust ports arranged to register with the cylinder port, means for continuously rotating the valve, and means for balancing the valve laterally, substantially as described.
9. An internal combustion motor comprising a plurality of cylinders, a valve chamber having a port opening into each of the
- cylinders, a conical rotary valve supported in the chamber, a piston connected to the valve and independent means connected to each cylinder for applying a pressure to the upper surface of the piston sufficient to balance the axial thrust of the conical valve, substantially as described. 70
10. An internal combustion motor comprising a cylinder, a valve chamber, a rotary valve supported therein, and means for balancing the thrust of the valve in one direction consisting of a piston rigidly connected to the valve, an auxiliary cylinder inclosing the piston and having a chamber formed therein, connections between the chamber and cylinder to allow a free transmission of pressure therebetween, and a dummy piston supported in the chamber and arranged to bear upon the face of the first mentioned piston, substantially as described. 75
11. An internal combustion motor comprising a plurality of cylinders, a valve chamber, a rotary valve supported therein, a piston rigidly connected to the valve, a cylinder inclosing the piston and having a plurality of chambers formed therein, connections between the cylinders and chambers to allow a free transmission of pressure therebetween, and a dummy piston located in each chamber and arranged to press firmly against the face of the first mentioned piston to prevent communication between the chambers, substantially as described. 80
12. An internal combustion motor comprising a plurality of cylinders, a valve chamber, a rotary valve supported therein, a piston rigidly connected to the valve, a cylinder inclosing the piston and having a plurality of chambers formed therein, connections between the cylinders and chambers to allow a free transmission of pressure therebetween, a dummy piston located in each chamber and arranged to press firmly against the face of the first mentioned piston to prevent communication between the chambers, an oil feed pipe communicating with the central portion of the cylinder, and an annular recess formed in the cylinder and having connection with a return pipe, substantially as described. 85
13. An internal combustion motor having, in combination, a cylinder, a piston operating therein, a valve chamber provided with a port opening into the cylinder, a valve supported in the chamber and having supply and exhaust ports arranged to register with the cylinder port, means for continuously rotating the valve, and fluid means for placing the valve in a condition of substantial static equilibrium, substantially as described. 90
14. An internal combustion motor having, in combination, a cylinder, a piston operating therein, a valve chamber provided with a port opening into the cylinder, a valve 120
15. An internal combustion motor comprising a cylinder, a piston operating therein, a valve chamber provided with a port opening into the cylinder, a valve 125
16. An internal combustion motor comprising a cylinder, a piston operating therein, a valve chamber provided with a port opening into the cylinder, a valve 130

supported in the chamber and having supply and exhaust ports arranged to register with the cylinder port, fluid means for balancing the valve both axially and laterally, 5 and means for exerting a slight excess pressure axially of the valve to firmly seal it, substantially as described.

15. An internal combustion motor comprising a cylinder, a valve chamber, a valve supported in the chamber, means for continuously rotating the valve, and fluid means for balancing the valve in synchronism with the changes of pressure in the cylinder, substantially as described.

16. An internal combustion motor having, in combination, a cylinder, a piston operating therein, a valve chamber provided with a port opening into the cylinder, a valve supported in the chamber and having a port arranged to register with the cylinder port, means for continuously rotating the valve, and means for balancing the valve laterally, substantially as described. 20
